APPARATUS FOR THE CHECKING OF A DIESEL ENGINE

Gérard Henri Augustin Fourtané, Asnières, Seine, France,
assignor to Société d'Etude et de Fabrication de Ma-
terial Electronique (SEFME) S.A.R.L.

Filed Sept. 29, 1964, Ser. No. 399,971
4 Claims. (Cl. 73—119)

The problem of the complete checking of diesel engines during operation has not yet been met with any fully satisfactory solution.

In fact, the rational checking of a diesel engine must necessarily comprise:

- (a) the checking of the injection and of the injectors,
- (b) the checking of the initial advance (timing of the pump), and of the curve of the automatic advance (if it occurs),
- (c) the checking of the engine operation (control of the overspeed cut-off, control of the idling).

With the previously known devices, these different verifications are made independently.

It is already known to check the calibration of the injectors by making up the injectors and trying them out on the test bench.

It is known to check a pump for a diesel engine by using a test injector or "false injector" in order to test, by stroboscopic means, the timing and the operational rhythm of the pump.

It has on the other hand been proposed to transform the energy of the fuel projected by the pump at each injection into an electric signal which, when suitably used, gives indications on the operation of the pump (speed of rotation for example).

There does not exist any apparatus which permits testing during operation of the different elements of a diesel engine without having recourse in one manner or another to a standard reference element; the injectors are tested on the bench with the aid of a control machine, which one can consider as a reference pump or compressor. The pumps on their part are tested with the aid of a test injector.

The present invention relates to a method and apparatus for the checking of a diesel engine during operation, without the use of a reference element.

According to this method, and with the aid of this apparatus, one checks successively the injection, and more particularly the opening times of the various injectors, the injection pump being that of the engine, then, the injectors being tested and adjusted, the operation of the pump, and more particularly its initial advance and its advance curve, the pump normally supplying the engine injectors, finally the operation of the engine and more particularly the operation of cut-off and idling.

Thus, the different elements of the engine are checked in their actual working conditions and not in isolation.

The invention relates equally to an assembly for the measure and checking of a diesel engine during operation, comprising essentially an adjustable transducer device capable of being connected into the inlet of each injector and to the outlet of the pump, this device transforming the variations in pressure at the points under consideration into an electric signal which is periodically interrupted and of which the duration (of emission or non-emission) and the frequency are equally characteristic; a measuring box making use of this duration and frequency, the duration of the signal corresponding to an indication of "time open," the frequency corresponding to a tachometric indication; a stroboscopic lamp which flashes at the frequency of the signal, or at a multiple of this

2

frequency; phase adjusting means enabling the phase of the flashes of the lamp to be adjusted in relation to the signal, this phase adjustment appearing on the measuring box in the form of an indication of "advance."

The following description and the accompanying drawings, which are given above all by way of non-limiting examples, will make better understood the manner in which the invention can be put into effect.

In the accompanying drawings

FIGS. 1, 2 and 3 represent respectively an elevation and two transverse sections at 90° of the transducer according to the invention;

FIG. 4 represents diagrammatically the assembly according to the invention;

FIG. 5 represents the front face of the measuring box; and

FIG. 6 represents the stroboscopic device which is used.

A transducer device of the single-contact type which is mounted at the inlet of the injectors or at the outlet of the pump of a diesel and transduces the pressure variations at its positions into a periodic signal is already known. Such device comprises essentially a chamber in which the fuel emerging from the pump or about to enter the injector arrives, the chamber, at the opposite end to the arrival of the fuel being closed by a piston provided with a helical return spring, the displacements of the spring causing the opening (or closing) of an electric circuit, from which the production of a pulsed signal enables the frequency to be theoretically obtained.

However, such a device presents serious drawbacks:

(a) In practice, the use of a helical spring results in parasitic vibrations rendering the apparatus imprecise;

(b) An empirical adjustment of the tension of the springs envisaged "until the appearance of the required electrical pulsations." It was supposed that, as a result of this empirical adjustment, the beginning (or the end) of an electric pulsation corresponded to the beginning (or the end) of an injection;

(c) In fact, even in the best conditions, it was found that this apparatus was unusable, except for the use of the periods of the signal which it created, which could be translated for example into an indication of the speed; the apparatus was completely useless for the measurement of injection time, the start of movement of the piston did not correspond necessarily to a determining instant of the injection.

The transducer according to the invention avoids these drawbacks.

More precisely, the transducer according to the invention for the transformation of variations of pressure at the inlet of the injectors or at the outlet of the pump of a diesel engine comprises essentially a cylindrical connecting head, capable of being mounted, with the aid of

appropriate fittings, in the stream of the relevant connecting pipe, a cylinder, extending transversely of the connecting head, a cylindrical adjusting head placed at the end of the cylinder opposite to the connecting head and on the axis of the latter, a piston movable in the cylinder between the connecting head and the measuring head, this movement corresponding to the opening or the closing of a circuit, thus giving rise to an electric signal, the end of the piston corresponding to the connecting head being pushed back by the pressure obtaining in the connecting head, the end of the piston corresponding to the measuring head being applied against a leaf spring mounted in the measuring head, the tension of the leaf spring being adjustable by means of an adjustment ring threaded on the outside of the measuring chamber and

pressing against the ends of the leaf spring, this ring carrying directly a graduation corresponding to different calibrations of the injectors, such that the electric signal

produces, when the connecting head is mounted on a conduit leading into an injector, corresponding in duration (of emission or of non-emission) to the time during which the pressure in the conduit is greater than the set calibration pressure, that is to say for an injector adjusted to this calibration pressure, at the time of injection.

Thus, one can not only use the frequency of the signal thus produced (to measure for example the number of injections per unit of time), but also its duration.

FIGS. 1, 2 and 3 represent the new transducer according to the invention (FIG. 3 being a section on the line III-III of FIG. 1 and FIG. 2 a section on the line II-II of FIG. 3.)

The device according to the invention comprises an annular connecting head 1, a cylinder 2 connecting with the connecting head, a measuring head 3, mounted at the other end of the cylinder 2, these three elements forming part of a single body. The head 1 may, with the aid of appropriate fittings be mounted in series on a diesel engine, either upstream of the injectors or at the outlet of the injection pump, with its axis coinciding with the axis of the conduit or tube on which it is mounted.

In the interior of the cylinder 2 is slidably mounted a piston 4 carrying a sliding sealing joint 4a. The pressure in the interior of the connecting head 1 acts on the face 4b of the piston 4. At its other end, the piston 4 carries a bearing head 4c. This bearing head 4c is in contact with an assembly of leaf springs 5. These leaf springs have their ends 5a located in a channel 3a in the annular head 3.

They are held in place by an adjusting ring 6, which is threaded onto the chamber 3. This ring 6 carries a scale 6a which is movable in relation to an index 3a of the measuring head 3. This scale 3a indicates the adjustment of the tension of the springs 5 corresponding to the values of the calibrations of the injectors to be controlled. As long as the pressure in the head 1 is lower than the value corresponding theoretically to the opening of the injectors calibrated to the indicated value, the head 4c of the piston 4 remains in contact with a metal abutment 7 which is insulated by a plate 8. To this metal abutment 7 is connected two contacts or conducting connecting sockets 9. As long as the head 4c is in contact with 7, the latter is at the potential of the assembly 1, 2, 3 (to earth). As soon as the piston 4 begins to move, all electric contact between the piston 4 and the abutment 7 is broken. An electric circuit connected at 9 and having earth return by 9-7-4c-4-3-2-1 is open as soon as 4c leaves the abutment 7. Thus an electric circuit can be set up in which a signal is created which corresponds to the value of the pressure in 1, in relation to a value of the set calibration. The duration of this signal, more precisely with the indication of the length separating two successive electric impulses, corresponds very exactly to the time of opening of an injector calibrated to the set value. Of course, with another electric system, it is the true duration of the electric impulses which would be the useful value.

Advantageously, the cylinder 2 is bored with an opening 2a to get rid of any fuel which may have seeped past the ring 4a.

Preferably also, the adjusting ring 6 can be locked by a lock ring 10, screwed like it on the head 3, but with a different thread pitch.

Whatever its nature, the transducer delivers a signal which for the duration, as well as the frequency, is significant.

The signal is made use of in the following manner: The transducer T according to the invention is used in conjunction with a measuring box 11 (of which the front face is shown in FIG. 5) and a stroboscopic lamp 12, to carry out the complete control and adjustment of a diesel engine indicated by M.

The measuring box is supplied by a D.C. source S, which

advantageously is the vehicle battery (thus the earthing of the measuring box is itself assured at the same time as its supply) which is driven by the engine M. The box is moreover connected by a cable 13 to the transducer T (for the establishment of the detection circuit), and by a cable 14 to the stroboscopic lamp 12. This lamp comprises a button 12a which must be pushed to start its operation and a control button 12b for controlling the phase difference between the transducer signal and the light signal emitted by the lamp 12.

10 The front face of the measuring box (FIG. 5) comprises the following elements:

(a) At the top left an indicator dial showing the amount of advance and of injection on two scales. The first (greater scale) is graduated in engine degrees (0°-40°).

The second (smaller scale) in pump degrees (0°-20°). Between these two scales is the injection scale.

(b) Bottom left a switch knob STOP-PUMP TIMING-PUMP ADVANCE-INJECTION which selects the operations which, as will be seen, take place in a given interval.

(c) Top right the tachometer with two scales, of two sensitivities.

The first (upper scale)

25 0 to 1000 r.p.m.
0 to 5000 r.p.m.

indicates the engine speed.

The second (lower scale)

30 0 to 500 r.p.m.
0 to 2500 r.p.m.

indicates the pump speed.

(d) Bottom right the switch which selects the sensitivity of the tachometer.

(e) Bottom centre: the connecting socket 14 for the lamp 12.

The reading "injection" corresponds to the length of time separating two impulses in the signal from the transducer T. The tachometer readings correspond to the frequency of this signal. The readings of advance correspond, as will be seen, to the phase difference which has been created between the signal from the transducer T and the frequency of operation of the stroboscopic lamp 12.

45 The assembly according to the invention is made use of in the following manner:

(1) Preparation for the checks

50 In order, it is convenient to identify the vehicle so as to know from the maker's specifications:

the setting of the injectors

the timing of the pump in degrees in relation to TDC

55 the curve of advance if the pump is provided with automatic advance.

If the engine does not carry the marking TDC either on the flywheel or on the crankshaft pulley, it is convenient first of all to determine the latter with the greatest precision by "dropping a valve" according to the customary method. The flywheel is then marked with a fixed reference mark.

(2) Measurements

65 (A) *Checking the injection.*—The graduation of the transducer T being adjusted according to the setting given by the constructor, a series of measurements of "injection time" is made by connecting successively the transducer upstream successively of each of the injectors of the engine.

On the scale "injection" of the left-hand dial, readings are taken which, if the injectors are suitably adjusted, should correspond to the predetermined values.

75 For example, in a four-cylinder engine readings are

taken on moving the pick-up from the 4th to the 3rd then to the 2nd and to the 1st injection circuit as follows:

cylinder 4: 1.5
cylinder 3: ¹ 1.5
cylinder 2: 2.2
=====

cylinder 1: 1.5

¹ The predetermined value being 1.5.

Injector No. 2 is to be removed: it is either too strongly 10 adjusted or sticking.

In another example: on a 4-cylinder engine readings are taken in the same manner.

cylinder 4: 1.5
cylinder 3: 1.0
cylinder 2: 1.5
=====

cylinder 1: 1.5

Before removing injector No. 3 on which the setting is probably too low, the tachometer is adjusted to the range 2500/500 and the engine is progressively accelerated. If the tachometer follows the increase in engine speed in a normal manner, the injector setting is definitely too low. On the other hand if during the course of the acceleration a sudden break occurs (return of the needles of the two dials to zero), the engine continuing to accelerate, it is a question of a fault in the sealing-tightness of the pump cylinder. The latter should therefore be removed.

In the opposite case, the injector being removed and adjusted or replaced, new readings are taken on the same circuit. If the lowest reading is still obtained, the pump is to be suspected. If in the course of an injection test the needles of the measuring apparatus move erratically, this indicates intermittent sticking of the injector. If the needles remain at zero, the injector has stuck in the open position.

(B) *Checking the initial advance.*—The injection control being finished, the pick-up is mounted on the first injection circuit at the outlet of the pump (or the last circuit).

(a) If the flywheel or the crankshaft pulley comprises a mark *injection instant*, the control switch (bottom left on the front face of the control box) is set to PUMP TIMING. The stroboscopic lamp is pointed at the flywheel or the pulley, and the control button pressed with the engine running at idling speed: the mark "injection instant" should then be opposite the fixed index, the pump timing being then correct. Should this not occur, the pump timing is retarded if the movable mark is in advance of the fixed mark and the pump timing is advanced if the moving index mark has passed the fixed mark, until coincidence of the two marks is obtained.

(b) *The flywheel or crankshaft pulley carrying the mark TDC.*—In this case, the initial advance determined by the maker is known. The operating switch is adjusted to ADVANCE. With the aid of the knurled phase adjustment knob 12b situated on the stroboscopic lamp 12, the predetermined number of degrees of advance is set on the scale "engine advance"; the stroboscopic lamp is pointed at the flywheel or the pulley, the button 12a is pressed, with the engine idling: the mark TDC should then coincide with the fixed mark if the pump is correctly timed. Should this not occur, the reading on the scale "engine advance" is read by adjusting with the aid of the knurled knob the phase difference between the two marks when coincident. This permits the mistiming to be measured and indicates to the operator the correction to be applied according to the same method as described in the preceding paragraph.

(C) *Checking the automatic advance curve.*—When the injection pump is provided with an automatic advance device, the control of the different values of this curve specified by the maker is carried out by repeating the operation described above under different operating con-

ditions and noting the angular values and the engine operating conditions for each of them.

In the case of an automatic advance device which has stuck, the latter may occur at the lower part or in the middle or at the upper part of the range of the curve. In the case of an advance device which sticks in the middle of the range, one first of all checks the operation of the initial timing control for an exaggerated initial advance; on accelerating up to the cut-off condition, this advance would remain fixed.

If the different top dead centres of an engine are known and if they are marked on the flywheel or the crankshaft pulley, the injection advance of each cylinder can be verified and by deduction the cam angles of the pump can be measured. In the case of a pump having adjustable push rods, it would be easy to correct these angles should this be necessary.

(D) *Verification of the cut-off operation.*—This verification is carried out with the aid of the tachometer using the scale 2500/5000. This verification is very important: operation at a speed lower than that specified by the maker results in poor performance. On the other hand, operation at a higher speed reduces the life of the engine.

(E) *Idling adjustment.*—This is also effected with the aid of the tachometer using the scale 500/1000, reference being made to the maker's specifications.

Thus, the apparatus according to the invention permits complete and rational checking of all the elements of 30 a diesel engine. This is effectively obtained by the use of a transducer giving a signal which has a real significance both in respect of its duration and its frequency. This being so, the invention is of course not limited to the embodiments described but extends to all 35 the variants conforming to the spirit of the invention.

What is claimed is:

1. A device for sensing duration of injection of a fuel injection system particularly a diesel engine fuel system having injectors comprising a tubular member 40 having a first end with means for connecting this end to a fuel line to be measured and for establishing communication of the interior of said tubular member with the fuel line, said tubular member having a second opposite end with a head portion, an electrical contact disposed adjacent the juncture of said tubular member and said head portion, a piston having a first end subjected to the fuel pressure in said fuel line and being movable in said tubular member in response to a predetermined pressure in said fuel line, said piston having a bearing head adjacent its opposite end engageable with said contact and being movable away from said contact only upon the occurrence of a predetermined pressure in the fuel line, spring means biasing the piston to maintain the head portion in engagement with said contact, adjustable setting means carried by said tubular member acting on said spring means to maintain its biasing force on said piston to an amount preventing the movement of said piston head portion away from and out of contact with said electrical contact except upon the attainment in the fuel line and said tubular member of a predetermined setting pressure comparable to the theoretical opening pressure of the injector associated with the fuel line, and electrical sensing means connected to said contact for sensing 55 when said piston member is engaged and when it is disengaged from said contact, said spring means comprising a spring beam, means in said head portion for holding each end of said spring beam adjacent said piston head portion, said adjustable setting means including an adjusting member carried by said head portion and being movable in respect thereto against said spring beam adjacent each end thereof for varying the biasing pressure of said spring means against said piston and thus the pressure of the fuel at which the piston will move.

2. A device according to claim 1, wherein said adjusting member comprises a ring threaded onto said head portion, and a locking ring for locking said adjusting ring in an adjusted position.

3. A device according to claim 2, wherein said adjusting ring includes a scale defined around the periphery thereof, said head portion having an index disposed for orientation with said scale.

4. A device according to claim 1, wherein said sensing means includes a measuring box having means for indicating when the theoretical pressure is exceeded, and a stroboscope lamp connected to said measuring box for checking the readings in accordance with the indicated rotational speed of the engine and the injector.
